ARTICLE OF FOOTWEAR

Edward P. Bullard III, Fairfield, Conn.

Application March 16, 1950, Serial No. 149,997

6 Claims. (Cl. 2-239)

1

This invention relates to athletic footwear, particularly to that type used in sports which require a relatively heavy boot being securely laced to the wearer's foot. A ski boot, for example, must be so tightly laced as to insure the user's foot being held rigidly secured to the associated ski. This requisite tight lacing is sometimes extremely uncomfortable, so much so as to frequently require loosening at the end of a run, which in turn necessitates re-tightening before the next run.

An object of this invention is to provide an improved article of footwear constructed and arranged to permit an athletic shoe such, for example, as a ski boot, being secured to the wearer's foot with any degree of tightness required to insure substantial rigidity between the foot and boot, and entirely without discomfort.

A further object is to provide an improved sock constructed and arranged to insure the necessary tightness of an ordinary ski boot or the like without requiring the boot itself to be tightly laced.

A further object is to provide a positioning device arranged to insure and maintain the correct positioning of the wearer's foot in a shoe, ski boot or the like, so that the foot is held firmly in the angle between the sole and upper along the inner side of the shoe.

With the foregoing and other objects in view, I have devised the construction illustrated in the accompanying drawing forming a part of this specification. It is, however, to be understood the invention is not limited to the specific details of construction and arrangement shown, but may embody various changes and modifications within the scope of the invention.

In the drawing:

Fig. 1 is a side elevation showing one embodiment of the invention in use on a wearer's foot;

Figs. 2 and 3 are sections on the lines 2-2 and 3-3 respectively, of Fig. 1, and

Fig. 4 is a partial elevation showing the opposite side of the foot from Fig. 1.

For the purposes of disclosure, the invention is shown employed with a ski boot 11 having the usual sole 12 and upper 13 provided with hooks 14 for use in lacing the boot to a wearer's foot 15. A characteristic of all ski boots is the rigid, non-flexing nature of the sole and heel portion thereof. These boots are constructed in a manner to prevent any flexing between the sole and heel and often employ a rigid metal plate extending from the heel to the sole forming one of the laminae of the sole and heel construction. The

present invention provides an inflatable device or bladder that permits the relatively loose lacing of such boots to avoid discomfort to the wearer while providing an arrangement which, when inflated, insures the requisite high degree of rigidity between the foot and the boot required in various sports, such as skiing.

Referring to the drawing, the inflatable device is shown as applied to a sock 16 of textile material which forms the entire inner surface of the sock in contact with the wearer's foot. In the embodiment disclosed, the sock 16 is shown as provided with an inflatable section covering an area on the top of the wearer's foot over the instep and along the outer side of the foot from a point forward of the instep to a point near the heel, and a second inflatable section on the outside of the foot connected to the first section and extending along the back of the foot at the inner side of the heel.

As illustrated, an inflatable bladder 17 of fluid tight material, such, for example, as rubber, has inner and outer walls 18 and 19 respectively, connected at their edges 21. The bladder 17 in the embodiment disclosed forms an integral part of the sock. As illustrated, the inner wall 18 can be adhesively secured to the outside face of the textile material 16, or the bladder can be incorporated in the sock to form a part of the wall thereof, in any manner desired. As shown in Fig. 1, the bladder 17 is so shaped as to cover the top of the wearer's foot under the boot vent 22 and tongue 22a over the instep, and also along the outer side of the foot from a point forward of the instep to a point adjacent the heel 23. The bladder 17 is formed so as to leave an opening 24 over the outside ankle 24a of the wearer uncovered, and the inside ankle 25 is also left uncovered by the bladder. The bladder 17 includes a section 26 located in back of the outside ankle to fill the space between this part of the foot and the shoe or boot 11. The bladder 17 is formed to extend across the top of the foot past the vent 22 far enough to provide a pressure absorbing cushion over the arch of the foot so that the latter is cushioned against concentrated pressure produced by tight lacing. An additional bladder section 28 on the inside of the foot is so located as to fit the area at the rear of the inside ankle 25 above the heel.

By applying the inner wall 18 of the bladder to the material of the sock in any suitable manner, adhesively or otherwise, the bladder forms an integral part of the sock 16 which in no way

affects the ease with which it can be put on or taken off by the wearer.

The bladder 17 is preferably formed to extend upwardly above the wearer's ankle, and below the top of the ski boot or the like, and means is provided for inflating and deflating the bladder after the boot is laced over it. As illustrated, this includes a spring pressed check valve 31 connected to the outer end of a tube 32 communicating with the inner space of the bladder 17, and extending upwardly to a point above the boot 11. A valve stem 33 is accessible from the outer end of the tube for opening the valve for deflating the bladder. The valve 31 can have any desired construction, such, for example, as that used in valves for pneumatic tires; or the like.

In use, the sock is applied to the foot by the user in the usual way, the bladder being deflated at the time, and a shoe or boot, such as the ski boot 16, is put on over the sock in the usual manner and then laced up relatively loosely so as to produce no uncomfortable pressure on the foot. After lacing, any degree of tightness can be obtained without any discomfort whatever by inflating the bladder 17 by any suitable means, such, for example, as a small hand pump or the like (not shown) which is first connected to the valve tube 32. The check valve 31 retains the pressure in the bladder as long as desired. Before removing the boot the valve stem 33 is pressed inwardly to deflate the bladder, after which the boot is removable upon unlacing. In place of a separate hand pump a rubber bulb pump with suitable valving can be permanently connected to the bladder for inflating and deflating, if desired.

As shown, more or less exaggerated in Fig. 2, the main section of the bladder 17 holds the wearer's foot in correct position against the inner side of the boot and presses it firmly into the angle 35 formed between the upper 13 and the sole 12 along the inner side of the boot. The bladder sections 26 and 28 fill the spaces above the heel 23 in back of the outer and inner ankles, respectively, and the section 27 holds the foot firmly against the sole with the effect of tight lacing without its discomfort. Likewise the sections 26, 28 above the heel act to press the heel firmly down on the sole of the boot. The foot is maintained rigid with the shoe, as is essential in many sports, such, for example, as skiing, but entirely without discomfort.

The invention can be variously modified and adapted within the scope of the appended claims.

Having thus set forth the nature of my invention, I claim:

1. An article of footwear for use inside a ski boot or the like having a rigid, non-flexible sole and heel portion including an inflatable bladder so located as to cover the upper surface and the outer side surface of the foot from a point forward of the instep to a point adjacent the heel, and located, when worn, entirely within said ski boot or the like; and means including a valve to permit inflating said bladder after being placed on a wearer's foot and after a ski boot or the like is secured to the foot on which said article of footwear is located, whereby the sole and heel of the wearer's foot are maintained in intimate contact with the rigid, non flexible sole and heel of the ski boot and the inner side of the wearer's foot is pressed firmly against the inner side of said associated boot.

2. An article of footwear for wear inside a ski

boot or the like comprising a sock having an inflatable bladder forming a part thereof and so located as to cover an area on the top of a wearer's foot over the instep and along the outer side of the foot from a point forward of the instep to a point adjacent the heel, and located, when worn, entirely within said ski boot or the like; and means including a valve to permit inflating said bladder when the sock is worn under 10 a ski boot or the like whereby the bladder cushions the pressure of the boot on the top of the wearer's foot and simultaneously holds the inner side of the wearer's foot pressed rigidly into the angle between the sole and upper along the inner side of an associated boot.

3. An article of footwear for wear inside a ski boot or the like formed of textile material comprising a sock having an inflatable bladder of fluid tight material connected to said textile material so as to form an integral part of the sock so located as to cover an area on a wearer's foot over the instep and extending along the outer side of the foot from a point forward of the instep to a point adjacent the heel, and located, 20 when worn, entirely within said ski boot or the like; and means permitting inflation of said bladder when the sock is worn under a ski boot or the like whereby to cushion the pressure of said boot on the top of a wearer's foot and simultaneously press the wearer's foot rigidly into the angle between the sole and upper along the inner side of the associated boot.

4. A sock for wear inside a ski boot including a layer of textile material forming the entire inner surface of the sock, an inflatable section comprising a bladder forming an integral part of the sock and so located as to cover an area on the top of a wearer's foot over the instep and along the outer side of the foot from a point forward of the instep to a point adjacent the heel, and valve means connected to said bladder and so located as to permit inflating said bladder after a boot is laced over the sock to thereby cushion the pressure of the laced boot on the top of the foot and simultaneously apply sufficient pressure over said area to hold the wearer's foot firmly in the angle extending along the inner side of the boot between the sole and upper thereof.

5. A sock for wear inside a ski boot including a layer of textile material forming the entire inner surface of the sock, an inflatable section comprising a bladder secured to the outer surface of the textile material so as to form an integral part of the sock and cover an area on the top of a wearer's foot over the instep and along the outer side of the foot from a point forward of the instep to a point adjacent the heel, and valve means connected to said bladder and so located as to permit inflating said bladder after a boot is laced over the sock to thereby cushion the pressure of the laced boot on the top of the foot and simultaneously apply sufficient pressure over said area to hold the wearer's foot firmly in the angle extending along the inner side of the boot between the sole and upper thereof.

6. A sock for wear inside a ski boot including a layer of textile material forming the entire inner surface of the sock, an inflatable section comprising a bladder secured to the outer surface of the textile material so as to form an integral part of the sock and cover an area on the top of a wearer's foot over the instep and along the outer side of the foot from a point forward of the instep to a point adjacent the heel, said bladder having sections forming parts of the sock and so

positioned as to extend along the back of the wearer's foot above the heel and in back of both inner and outer ankle bones, and valve means connected to said bladder and so located as to permit inflating said bladder after a boot is laced over the sock to thereby cushion the pressure of the laced boot on the top of the foot and simultaneously apply sufficient pressure over said area, including the area above the wearer's heel, to hold the wearer's foot firmly in the angle extending along the inner side of the boot between the sole and upper thereof, and press the wearer's heel downwardly into the boot.

EDWARD P. BULLARD III.
